G. W. CURTIS

RAIL BENDER

Filed Nov. 7, 1923

FIG.1.

FIG. 2.

FIG. 3.

FIG. 4.

Inventor,

George W. Curtis.

By William W. Deane

his Attorney

UNITED STATES PATENT OFFICE.

GEORGE W. CURTIS, OF JACKSONVILLE, FLORIDA.

RAIL BENDER.

Application filed November 7, 1923. Serial No. 673,315.

To all whom it may concern:

Be it known that I, GEORGE W. CURTIS, a citizen of the United States, residing at Jacksonville, in the county of Duval and State of Florida, have invented certain new and useful Improvements in Rail Benders, of which the following is a specification.

This invention relates to improvements in bending tools and particularly to bending tools for rails and the like.

The primary object of the invention is to provide a simple, inexpensive bending tool capable of exerting great pressures on a rail or the like for the purpose of bending the rail sharply or gradually.

Another object of the invention is to furnish a rail bender which is reversible, that is, one which may be turned upside down to grip either side of the head of the rail or which may be used at either side of the head of the rail in reversed positions.

A further object of the invention is to provide a rail bender having a beam provided at one end with an outwardly extending abutment recessed at opposite sides of its extremity in order to abut against either side of the head of a rail.

A still further object of the invention is to furnish a rail bender with a gripping member designed to grip either side of the head of a rail and to be reversed to engage either side of the head of a rail.

Another object of the invention is to provide a bending head swivelled to an adjusting screw and provided with a diametrically arranged lug designed to abut against either side of the head of a rail.

A further object is to furnish a rail bending tool having an L-shaped beam provided at one end with an abutment to engage either side of the head of a rail and provided at its opposite end with a reversible bending head, and a reversible gripping member adjustably mounted on the beam between the ends of the latter.

With the foregoing objects outlined and with other objects in view which will appear as the description proceeds, the invention consists in the novel features hereinafter described in detail, illustrated in the accompanying drawing and more particularly pointed out in the appended claims.

Referring to the drawing:

Figure 1 is a perspective view of the improved bending tool illustrated applied to a rail.

Fig. 2 is a top plan view of the tool.

Fig. 3 is a vertical transverse sectional view taken on line 3—3 of Fig. 2.

Fig. 4 is a similar view taken on line 4—4 of Fig. 2.

In the drawing, 1 designates a strong metal beam provided at one end with an angular extension or foot 2 terminating in an abutment head 3 having a horizontally disposed central flange 4 designed to rest with either of its upper or lower surfaces on the upper surface 5 of the rail to be bent.

The head 3 is recessed as shown at 6 on opposite sides of the flange 4 in order to provide pockets on opposite sides of the head to receive the head of the rail. It may be seen from Fig. 1 that one of the pockets 6 is engaging the head of the rail and it will be apparent that the opposite pocket may engage the head of the rail when the beam 1 is turned upside down or reversed.

The opposite end of the beam 1 is provided with a threaded aperture to receive the screw 7. This screw has apertures 8 at its outer end to receive a lining bar (not shown), employed to turn the screw. The inner end of the screw is provided with a spool-shaped head 9 on which a bending head 10 is swiveled, the bending head being held in place by a screw 11 which extends into the groove of the head 9. The screw 11 prevents the head 10 from passing axially off of the head 9 while permitting rotation of the heads 9 and 10 relatively to one another. The bending head is provided with a diametrically disposed flange or lug 12 which, similar to the lug 4, is adapted to engage the surface 5 of the head of the rail, and it is obvious that the lug 12 also permits operation of the bending head when the beam 1 is reversed or turned upside down, that is, the bending head is also reversed.

Slidably mounted on the beam 1 intermediate the ends of the latter, is a substantially T-shaped gripping member 13 having an aperture 14 through which the beam 1 passes. The head of this gripping member has recesses 15 at opposite sides of its web 16, and as shown in Fig. 1, one of these recesses is engaging the head of the rail while the other recess lies above said head. When the beam 1 is reversed, it is obvious that the uppermost recess 15 may be brought into engagement with the head of the rail.

In operation, the parts may be arranged as shown in Fig. 1, and then a liner bar may

be inserted in one of the apertures 8 for the purpose of turning the screw 7. As the screw turns, the gripping member 13 will function as a fulcrum and the rail will 5 be bent about this point. As shown in Fig. 1, the device is arranged to bend the rail toward the left or in a counter-clockwise direction. If it is desired to bend the same toward the right or in a clockwise direction, 10 the parts are turned upside down, so that the uppermost recesses 6 and 15 engage opposite sides of the head of the rail, and then when the screw 7 is turned the rail will be bent toward the right. The flange 12 of 15 the bending head, will of course lie on the upper surface of the rail during the bending in either direction.

From the foregoing it is believed that the construction, operation and advantages of 20 the invention may be readily understood but it is believed desirable to point out that in using this rail bender for switch-work, the operator may stand in front of the switch, so that he may be occupying a safe place. 25 The device can be used by construction gangs for breaking or bending rails, and with this device as little as six inches may be broken off the rail, while with other types of rail breakers it is necessary to waste from 30 fifteen to eighteen inches of the rail. The device is preferably of such length that adjustment may be made from six to eighteen inches, so that a piece lying between these sizes may be broken from the rail if desired. 35 The device may be used for switch-work where the switch rail leads either to the right or left. The operator can stock either side with this rail bender and work in front of the switch with absolute safety. 40 It is obvious that changes may be made in the details disclosed without departing from the spirit of the invention as expressed in the claims.

What is claimed and desired to be secured by Letters Patent is:

1. A rail bender including a beam provided at one end with an abutment head having upper and lower recesses, either one of which may receive the head of a rail, a 50 gripping member slidably mounted on said beam and adapted to hook over the head of a rail, and a bending head provided at the opposite end of said beam and provided with a screw for moving the same away from 55 said beam.

2. A rail bender including a beam pro-

vided at one end with an abutment head adapted to engage either side of the head of a rail, a substantially T-shaped gripping member slidably mounted on said beam and having oppositely extending hooks designed to engage either side of the head of a rail, and a screw threaded in the opposite end of the beam provided with a bending head adapted to engage either side of the head of 60 a rail.

3. A rail bender including an L-shaped metal beam having recesses provided on opposite sides of the foot of the L designed to engage either side of the head of a rail, a gripping member slidably mounted on said beam and shaped to engage either side of the head of a rail, a screw threaded in the end of the beam opposite the end carrying the foot, and a bending head swiveled on 70 said screw and provided with a flange adapted to engage either side of the head of the rail.

4. A rail bender including a metal beam provided at one end with a threaded aperture and at its opposite end with an angular lug terminating in a head provided with an outwardly extending flange having recesses at its opposite sides to engage either side of the head of a rail, a gripping member slidably mounted on said beam and having oppositely extending hooks designed to engage either side of the head of a rail, a screw engaging the threads of said aperture, and a bending head swiveled on one 80 end of said screw and adapted to engage 85 either side of the head of a rail.

5. A rail bender including an L-shaped metal beam having a horizontally disposed outwardly extending flange arranged at the extremity of the foot of the L, upper and lower recesses in the foot arranged at opposite sides of said flange, each of said recesses being adapted to receive the head of a rail, a substantially T-shaped metal gripping member slidably mounted on said beam and having oppositely extending hooks, either one of which is adapted to grip the head of a rail, a screw mounted in the end of the beam opposite the end having the foot, and a head swiveled on said screw and having a diametrically extending flange adapted to engage either side of the head of 90 a rail.

In testimony whereof I affix my signature.

GEORGE W. CURTIS.
